UNITED STATES PATENT OFFICE.

MELVIN J. NAPIER, OF AKRON, OHIO.

OZONIZER.

1,379,776.

Specification of Letters Patent. Patented May 31, 1921.

Application filed April 8, 1920. Serial No. 372,338.

To all whom it may concern:

Be it known that I, MELVIN J. NAPIER, a citizen of the United States, and residing at Akron, in the county of Summit and State 5 of Ohio, have invented a new and Improved Ozonizer, of which the following is a specification.

This invention relates to devices for changing atmospheric oxygen from its common to the ozone state by means of electrical discharges, and its object is to provide an apparatus of this character which shall have great capacity for the space occupied and which shall have a uniform output. 10 15 A further object of this invention is to provide means for uniting medicinal vapors with the oxygen in the ozone state and for permitting a discharge thereof at a predetermined point.

20 This invention consists in combination with a source of comparatively high tension alternating current, preferably a transformer, of a chamber and a porcelain tube mounted therein and having its ends extending through the walls thereof, of electrodes mounted within and on the exterior of the porcelain tube, and wires connecting the two to this source of alternating current.

25 30 It further consists in providing a novel contact for the inner electrode and in the novel construction of this electrode.

It also consists in providing a cover for the chamber, preferably formed of glass, to hold the medicinal liquid which is to evaporate and mix with the ozone.

35 It also consists in inclosing this chamber in a case to retain the ozone laden atmosphere.

40 It also consists in providing means whereby a stream of water or other liquid may be broken up and presented to the ozone so that the ozone may be taken up by the water.

It also consists in the details of construction illustrated in the accompanying drawings and particularly pointed out in the claims.

45 In the drawings, Figure 1 is a vertical longitudinal section of this improved ozonizer. Figs. 2 and 3 are sections on the lines 2-2 and 3-3 respectively of Fig. 1. Fig. 4 is a horizontal section of one of the porcelain supporting tubes and of a pair of electrodes. Fig. 5 is an end view of an elec-

trode. Fig. 6 is a section illustrating a stop for the inner electrode.

Similar reference characters refer to like parts throughout the several views.

I have found that when a tube of porcelain is incased in an electrode and has mounted within it a second electrode, both electrodes being of less length than the porcelain tube, and when these electrodes are connected to a source of alternating electrical current of about 12,000 volts, that the atmosphere within the porcelain tube becomes highly charged with ozone. I have further found that when the inner electrode is spaced throughout its length from the porcelain tube so as to lengthen the electric sparks between the electrodes, that the effect is increased. I have found further that the effect is increased by placing a conical sheet-aluminum member within the inner electrode, although the reason for this is unknown to me at present.

50 55 60 65 70 75 80 85 90 95 100 105 In Fig. 4 of the drawings I have shown two supports 6 and 7, which are preferably of good non-conducting material such as earthenware, glass, vulcanite, gutta percha, or indurated fiber. Extending across and through proper openings in these supports and hermetically sealed therein is a tube 8 of porcelain around the outside of which is a metal tube 9, preferably of sheet aluminum, which constitutes one of the electrodes. This tube of aluminum may be continuous, or it may be split, as may be desired. Within the porcelain tube is a second electrode consisting of a shell 11 having a series of spacing points 12 which may be integral with the part 11 or mounted therein. Within this shell 11 is a conical member 10 which is connected at its larger end with the shell. The parts 10 and 11 are removable so they may be cleaned and are preferably split throughout their length so that the points 12 may be pressed against the inner wall of the porcelain tube 8 by the resilience of the parts 10 and 11. A connecting wire 13 extends from a transformer 14 to this outer electrode 9 which is preferably formed with a circumferential rib 15 to which this wire 13 may be connected, while a second wire 16 also extends from the transformer and is attached to a spring contact 17 which extends into the inner electrode 10 and contacts therewith. This contact 17 may be secured

to the support 7 by means of a bolt 18. In order to position the inner electrode, I have provided a stop 19 which may be secured to the support 7 by means of the bolt 20 and 5 which may have an inturned end 21. When the inner electrode is pushed into the porcelain tube 8 (from the left in Fig. 4) it will slip beneath the contact 17 and engage the end 21, at which time it will be in alinement 10 with the exterior electrode 9. Instead of the stop 19, a boss 8^a, shown in Fig. 6, may be formed on the inner surface of each tube 8 to limit the movement of the electrode 10.

The output of ozone of a mechanism of 15 this character will depend largely upon the quantity of current delivered by the transformer and by the effective areas of the electrodes. In the drawings I have shown nine porcelain tubes 8 mounted in the support 6 and have shown the outer electrodes 9 of 20 these various tubes connected by wires 22. I have also shown the wire 16 from the transformer 14 connecting to the branch wires 24, which branch wires extend through 25 holes 25 in the support 7 and connect to the ends of the contacts 17.

The lower ends of the supports 6 and 7 rest upon shoulders formed on the sides 27, 28 and 29 of the case and on the partition 30. All these joints are also hermetically sealed. It will be understood that this partition 30 may extend up to the top of the case, in which event the side 32 may be omitted as unnecessary. The side 32 is 35 shown to extend up from the bottom 33, and, together with the sides 28 and 29, supports a series of baffle plates 35, preferably of glass, which are removable to permit cleaning. A supply pipe 36 extends through the top of 40 the wall 32 and a drain pipe 37 through the bottom. When the device is in operation and the atmosphere within the case is being heavily charged with ozone, water or other liquids may be permitted to flow into the 45 case through the pipe 36 and take up this ozone, the baffle plates 35 being corrugated in order to break up the liquid and present as much surface thereof as possible to the charged atmosphere within the case.

50 As indicated in the drawings, the supports 6 and 7 extend between the side walls 28 and 29 of the case, but they are of less height than these side walls. Resting on the top of these supports is a shelf or cover 39, and 55 the joints between this shelf, the sides 27 and 28 and the supports 6 and 7 are all hermetically sealed. Resting on this shelf 39 is a tray 40, preferably of glass and having its upper surface provided with corruga- 60 tions 41. Small quantities of medicinal liquid, such as oil of eucalyptus, may be poured on this tray and spread all over these corrugations in a thin film to present an extended surface to the action of the ozone. The fine 65 particles of the liquids unite with the oxy-

gen of the ozone impregnated air and pass out through the opening 43 in the top 44. This top 44 extends over the entire case and its bottom may be provided with diagonal ribs 45 to stiffen it. 70

The side 27 is preferably provided with circular openings in alinement with the porcelain tubes 8 and into these openings the plugs 46 may be screwed, each being provided with an aperture 47 through which 75 air may enter. The holes for these plugs are of such size that electrodes 10-11 may be freely drawn out from the tubes 8 so that the electrodes and the interior of these tubes may be cleaned. When air or other gas or 80 vapor is forced into the case for any particular purpose, the majority of the openings 47 in these plugs may be closed and supply pipes connected to those remaining. In this case a conduit will be connected to 85 the cover at the opening 43 for the purpose of conducting the ozone laden air to a mask or nozzle for direct application of the ozonized vapors.

It is probable that when the ozone mixes 90 with the particles of oil that it changes to nascent oxygen.

By closing the opening 43 in the top cover and all of the openings 47 but one, the ozone 95 may be drawn from the case for direct application. In this case air may be permitted to enter through the remaining opening 47 and will flow through the several porcelain tubes 8.

Any desired means may be employed to 100 supply a primary current to the transformer 14. In the drawings two wires 50 and 51 are shown. I prefer the number of alternations of current to be from 600 to 1200 per second and while the primary may have any convenient voltage, the voltage of the secondary should be from 10,000 to 12,000 volts. 105

While under ordinary conditions there is little danger of short circuiting, it is often 110 advisable to fill the space around the transformer and the space between the supports 6 and 7 and around the tubes 8 with some hard insulating material. This prevents short-circuiting even if the device is submerged in water. 115

The details and proportions of the various parts of this device may all be changed by those skilled in the art without departing from the spirit of my invention.

I claim:-

1. In an ozonizer, the combination of a pair of supports, a porcelain tube mounted therein, and a pair of tubular electrodes, one on the outside and the other on the inside of the porcelain tube, the inner electrode 125 being cylindrical and having external projections to space it from the porcelain.

2. In an ozonizer, the combination of a pair of supports, a porcelain tube mounted therein, and a pair of tubular electrodes, 130

one on the outside and the other on the inside of the porcelain tube, the inner electrode being cylindrical and having external projections to space it from the porcelain 5 and also embodying a conical portion mounted within the cylindrical portion.

3. In an ozonizer, the combination of a pair of supports, a porcelain tube mounted therein, and a pair of tubular electrodes, 10 one on the outside and the other on the inside of the porcelain tube, the inner electrode being cylindrical and having external projections to space it from the porcelain and also embodying a conical portion mounted 15 within the cylindrical portion, both the cylindrical and conical portions being slotted longitudinally to permit the electrode to expand and hold itself in position in the porcelain.

20 4. In an ozonizer, the combination of a case and a pair of supports therein, a series of refractory tubes mounted in the supports, electrodes mounted within and around the refractory tubes, a transformer connected 25 to said electrodes, and means to conduct liquids across the ends of said refractory tubes between one of said supports and the adjacent side of the case.

5. In an ozonizer, the combination of a 30 case and a pair of supports therein, a series of refractory tubes mounted in the supports, electrodes mounted inside and outside the refractory tubes, a transformer and connections between the transformer and said electrodes, said case being formed with openings 35 in alignment with said tubes, plugs mounted in said openings, a tray resting on

said supports and adapted to receive medicinal liquids, and a cover for the case provided with a discharge opening.

40

6. In an ozonizer, the combination of a pair of supports, a porcelain tube mounted therein, a pair of tubular electrodes, one on the outside and the other on the inside of the porcelain tube, the inner electrode being 45 cylindrical and having external projections to space it from the porcelain, and a resilient contact member secured to one support and extending within the porcelain tube and the inner electrode and in engagement with 50 said inner electrode.

7. In an ozonizer, the combination of a pair of supports, a porcelain tube mounted therein, a pair of tubular electrodes, one on the outside and the other on the inside of the porcelain tube, the inner electrode being cylindrical and having external projections to space it from the porcelain, a resilient contact member secured to one support and extending within the porcelain tube and the 55 inner electrode and in engagement with said inner electrode; and a stop secured to the same support and extending within the porcelain tube to limit the movement of said inner electrode.

60

8. In an ozonizer, the combination of a dielectric tube and means for supporting the tube, a pair of tubular electrodes of aluminum, one on the outside of the dielectric tube and the other on the inside and spaced 70 therefrom, and conductors connecting to said electrodes.

65

MELVIN J. NAPIER.
